Related U.S. Application Data

(62) Division of application No. 29/398,503, filed on Aug. 1, 2011, now Pat. No. Des. 702,560.

CLAIM
The ornamental design for a cosmetic container, as shown and described.

(51) **LOC (10) Cl.** **09-01**

DESCRIPTION

(52) **U.S. Cl.**

FIG. 1 is an exploded top perspective view showing my new design for a cosmetic container;
FIG. 2 is a top perspective view showing the design in its assembled state;

(58) **Field of Classification Search**

USPC D9/600-681, 682-694, 516, 517, 719,
D9/529, 544, 563-575, 737, 739, 751, 721,
D9/506; D28/5, 76, 77, 91.1; 215/379,
215/382, 386; 220/376, 602, 662, 665, 669,
220/915; 222/153.13, 153.14, 175, 182,
222/183

FIG. 3 is a front elevational view of FIG. 1;
FIG. 4 is a front elevational view of FIG. 2;
FIG. 5 is a back elevational view of FIG. 1;
FIG. 6 is a back elevational view of FIG. 2;
FIG. 7 is a left side elevational view of FIG. 1;
FIG. 8 is a left side elevational view of FIG. 2;
FIG. 9 is a right side elevational view of FIG. 1;
FIG. 10 is a right side elevational view of FIG. 2;
FIG. 11 is a top view of FIGS. 1 and 2;

See application file for complete search history.

FIG. 12 is a bottom view of FIGS. 1 and 2;
FIG. 13 is a bottom perspective view of FIG. 1; and,
FIG. 14 is a bottom perspective view of FIG. 2.

(56) **References Cited**

All other surface(s) or portion(s) of my design not shown in the figures or otherwise described in the specification form no part of the claimed design.
